UNITED STATES PATENT OFFICE

PETER J. OTHS, OF WEST HAVEN, CONNECTICUT

DESIGN FOR A MAIL BOX

Application filed November 14, 1931. Serial No. 41,729. Term of patent 14 years.

To all whom it may concern:

Be it known that I, PETER J. OTHS, a citizen of the United States, residing at West Haven, in the county of New Haven and State of Connecticut, have invented a new, original and ornamental Design for a Mail Box, of which the following is a specification, reference being had to the accompanying drawings, forming part thereof.

Fig. 1 is a perspective view of a mail box showing my new design;

Fig. 2 is a front view of the same; and

Fig. 3 is a side view of the same.

I claim:

The ornamental design for a mail box as shown.

PETER J. OTHS.
